UNITED STATES PATENT OFFICE

EDWARD E. WALKER, OF ERIE, PENNSYLVANIA, ASSIGNOR TO ERIE MALLEABLE IRON COMPANY, OF ERIE, PENNSYLVANIA, A CORPORATION OF PENNSYLVANIA

METAL WHEEL

Application filed November 24, 1926. Serial No. 150,589.

In the forming of metal wheels, certain metal, such as malleable iron is very much more desirable in the forming of the hub and spokes than relatively harder metal, such as cast steel. There are several reasons for this. Malleable iron lends itself more readily to thin walled nicely formed castings and also can be more readily worked and machined after its formation. Thus it is practical to make a lighter wheel of such material and more cheaply than when formed of cast steel. The difficulty in using malleable metal for the hubs of driving wheels is that the walls of an ordinary key-way with which said hubs are provided are not sufficiently strong, or dense, to sustain the driving strains and shocks to which these walls are subjected. In consequence, it has been common to form wheels using malleable castings for the frame, or wheel structure outside of the hub and cast steel for the hub.

The present invention is directed to a means by which hubs of relatively soft metal, such as malleable iron may be successfully used and it consists broadly in supplying such hub with a metal insert of relatively hard metal, such as steel, and preferably steel that may be hardened for the key-way. Various ways of introducing the insert may be used. As exemplified in the present invention it consists in forming the key-way in a segment of metal and forcing it into a groove formed in the walls of the hub opening, preferably by a pressed fit. The strain on the comparatively small amount of metal of the key-way is then sustained by the relatively hard metal of the metal bar. The malleable, or soft metal of the hub will readily sustain the strain incident to the metal bar because a great deal larger surface is interposed in receiving the strains than would be practical, in an ordinary key-way and because the steel bar, being in the nature of a permanent fit in the groove, can be pressed into the groove so tightly as to prevent, under all conditions, any initial movement of the bar in the groove.

While the invention is applicable to malleable hubs in which the wheel frame is formed separately from the hub a full real-

ization of the invention is only secured where the hub and wheel frame, or spokes are integral. This utilization of the malleable metal for the hub, which is also the preferable metal for the wheel frame, permits of making these two parts integrally so that the weight incident to a joint between these parts may be saved and thus the wheel as a whole made lighter and cheaper. Both of these features are of importance, particularly the lighter weight because the wheels are what is known as unsprung weight and all saving possible here is particularly desirable. Features and details of the invention will appear from the specification and claim.

The invention as exemplified is illustrated in the accompanying drawings as follows:

Fig. 1 is a side elevation of the wheel.

Fig. 2 a section on the line 2—2 in Fig. 1.

Fig. 3 an enlarged view of the hub, partly in section, on the line 3—3 in Fig. 4.

Fig. 4 a section on the line 4—4 in Fig. 3.

Fig. 5 a side elevation of a wheel in which the spokes are formed separately from the hub.

Fig. 6 a section on the line 6—6 in Fig. 5.

Fig. 7 a section on the line 7—7 in Fig. 8.

Fig. 8 a side elevation of the hub, partly in section, on the line 8—8 in Fig. 7.

In the construction shown in Figs. 1—4, 1 marks the hub and 2 the spokes. The spokes are formed integrally with the hub. 3 marks the felloe and 4 the rim. The rim is provided with a beveled surface 5 seating on the felloe. A clamping ring 6 operates at the outside of the rim and this is actuated by a clamping plate 7 drawn up by clamping bolts 8, this rim structure forming no part of the present invention.

A tire 9 is arranged on the rim and a brake drum 10 is secured to the inside of the hub by bolts 10a. A hub sleeve 11 has the usual tapered opening 11a in which is arranged the tapered end 12 of the axle, the outer end of the axle being screw-threaded at 14 and provided with a nut 15 by means of which the hub is forced on to the tapered portion of the axle.

The axle is provided with the usual key-

seat 13 in which is placed the key 16. This key operates in a key seat 17 in the hub. The key seat 17 is in a key seat insert 18, as shown of segmental form, and arranged 5 in a groove 19 in the wall of the opening of the hub.

The hub and its spokes are preferably formed of a relatively soft metal, such as malleable iron and the key seat insert is 10 preferably formed of steel, or relatively hard metal, and is preferably secured in the groove 19 by being pressed into place so as to make a very tight pressed fit. This when pressed in with sufficient force secures the 15 key seat insert in a permanent manner in the hub opening.

With this construction all the advantages of the relatively soft metal wheel are obtainable and it is practical to make the 20 spokes and hub integral in that the same material may be used advantageously for both. This reduces the weight very materially and also the cost of the wheel.

In the alternative construction shown in 25 Figs. 5, 6, 7 and 8, the wheel spokes, or wheel frame, is formed separately from the wheel hub. The wheel hub has its sleeve 1a with an interior flange 1b against which the inner ring of the spokes 2a are placed. 30 A flange 1c is placed opposite the flange 1b and bolts 1d extend through the flanges and the spoke ring and thus the spokes are clamped in the hub. Otherwise the structure is similar to the structure illustrated 35 and described in Figs. 1 to 4.

Preferably the thrust surface of the hub engaged by the insert is greater than the thrust surface of the metal in the axle and preferably the engaged surface in the hub 40 is enough greater than the engaged surface of the axle to compensate for the difference in the thrust resisting capabilities of the metal.

What I claim as new is:—

45 A metal wheel hub formed of relatively soft malleable cast metal having an axle opening therein with a key-sustaining insert of relatively hard metal permanently secured in the walls of the opening and provided with key shoulders on its inner face, 50 the walls of the opening including the inner face of the insert forming an all-metal seating surface for the opening.

In testimony whereof I have hereunto set 55 my hand.

EDWARD E. WALKER.
